[57] **CLAIM**

The ornamental design for a siderail for an article carrier, as shown and described.

DESCRIPTION

FIG. 1 is a perspective view of a siderail for an article carrier showing our new design;

FIG. 2 is a top plan view thereof;

FIG. 3 is a right side elevation view thereof;

FIG. 4 is a left side elevation view thereof;

FIG. 5 is an enlarged fragmentary right side elevation view of the end portion within the circle 5 in FIG. 3;

FIG. 6 is an enlarged fragmentary left side elevation view of the end portion thereof within the circle 6 in FIG. 4;

FIG. 7 is an enlarged cross sectional view thereof taken along the lines 7—7 of FIG. 3; and

FIG. 8 is an enlarged cross sectional view thereof taken along the lines 8—8 of FIG. 4.

The broken lines are for illustrative purposes only and form no part of the claimed design.
